United States Patent Office

Des. 194,029
Patented Nov. 13, 1962

194,029

AUTOMOBILE

Lawrence Shinoda, Royal Oak, Mich., assignor to General Motors Corporation, Detroit, Mich., a corporation of Delaware

Filed July 5, 1962, Ser. No. 70,793

Term of patent 7 years

(Cl. D14—3)

Fig. 3

Fig. 4

FIGURE 1 is a side elevational view of an automobile according to my new design, the other side of the automobile being the same;

The dominant features of my design reside in the full line portions of the drawings.

I claim:

The ornamental design for an automobile, substantially as shown and described.
